CLAIM

The ornamental design for a set of artificial lash extensions as shown and described.

DESCRIPTION

FIG. 1 is a top left perspective view of a set of artificial lash extensions for the right eye and arranged in a specific order in a lash line of the right eye in accordance with the claimed design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a top right perspective view of a set of artificial lash extensions for the left eye and arranged in a specific order at a lash line of the left eye in accordance with the claimed design.

FIG. 9 is a front view thereof.

FIG. 10 is a rear view thereof.

FIG. 11 is a left side view thereof.

FIG. 12 is a right side view thereof.

FIG. 13 is a top view thereof.

FIG. 14 is a bottom view thereof.

FIG. 15 is a top left perspective view of a set of artificial lash extensions for the first eye and arranged in a specific order in accordance with the claimed design.

FIG. 16 is a top left perspective view of a set of artificial lash extensions for the first eye and arranged in a specific order in a curved manner in accordance with the claimed design.

FIG. 17 is a top view thereof.

FIG. 18 is a bottom view thereof.

FIG. 19 is a left side view thereof.

FIG. 20 is a right side view thereof.

FIG. 21 is a rear view thereof.

FIG. 22 is a front view thereof.

FIG. 23 is a top right perspective view of a set of artificial lash extensions for a second eye opposite the first eye and arranged in a specific order in accordance with the claimed design.

FIG. 24 is a top right perspective view of a set of artificial lash extensions for the second eye opposite the first eye and arranged in a specific order in a curved manner in accordance with the claimed design.

FIG. 25 is a top view thereof.

FIG. 26 is a bottom view thereof.

FIG. 27 is a left side view thereof.

FIG. 28 is a right side view thereof.

FIG. 29 is a rear view thereof; and,

FIG. 30 is a front view thereof.

The broken lines consisting of evenly spaced lines in the in the figures show portions of the set of artificial lash extensions that form no part of the claimed design. The broken lines consisted of evenly spaced lines illustrating environmental structures in the figures form no part of the claimed design.
